US00D948269S

(12) United States Design Patent (10) Patent No.: US D948,269 S
(45) Date of Patent: * Apr. 12, 2022

(54) BEVERAGE DISPENSER

(71) Applicant: Société des Produits Nestlé S.A.,
Vevey (CH)
(72) Inventor: Da-Mi Byun, Lausanne (CH)
(73) Assignee: SOCIÉTÉ DES PRODUITS NESTLÉ
S.A., Vevey (CH)
() Term: 15 Years
(21) Appl. No.: 29/693,450
(22) Filed: Jun. 3, 2019

(30) Foreign Application Priority Data

(57) CLAIM

The ornamental design for a beverage dispenser, as shown and described.

DESCRIPTION

FIG. 1 is a top, front, right perspective view of a beverage dispenser showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

The broken lines of even length illustrate the portions of the design that form no part of the claimed design.

The dot-dash-dot broken lines depict the boundaries of the claim and form no part thereof.

1 Claim, 7 Drawing Sheets
